UNITED STATES PATENT OFFICE.

EDWIN G. HINES, OF DRUMS, AND CHARLES S. MYERS, OF HAZLETON, PENNSYLVANIA; SAID MYERS ASSIGNOR TO SAID HINES.

DRAFT DEVICE.

1,399,300.

Specification of Letters Patent.

Patented Dec. 6, 1921.

Application filed May 29, 1920. Serial No. 385,278.

To all whom it may concern:

Be it known that we, EDWIN G. HINES and CHARLES S. MYERS, citizens of the United States, residing at Drums and Hazleton, respectively, in the county of Luzerne and State of Pennsylvania, have invented certain new and useful Improvements in Draft Devices, of which the following is a specification.

10 This invention relates to improvements in draft devices especially adapted for use in connection with plows.

An important object of this invention is to provide a device of the class described 15 having novel means for yieldably connecting the beam of a plow to a source of power so that, when the strain on the plow share is increased as the result of engaging a stump or other obstruction, the beam will be permitted to partake of a limited rearward movement with relation to the source of power, whereby a portion of the shock is absorbed.

A further object of this invention is to 25 provide a device of the class described having novel means whereby the connection between the plow beam and the source of power may be automatically broken as the load increases to an extent sufficient to break 30 the plow share or damage the same.

A further object of the invention is to provide a device of the class described having novel means whereby the cutting angle of the plow share may be readily and conveniently adjusted without interfering with 35 the ability of the device to absorb shocks and break the connection between the plow and the source of power when the load becomes excessive.

40 A further object of the invention is to provide a device of the class described which is of highly simplified construction, efficient in use and cheap to manufacture.

Other objects and advantages of the invention will be apparent during the course 45 of the following description.

In the accompanying drawings forming a part of this application and in which like numerals are employed to designate like 50 parts throughout the same,

Figure 1 is a side elevation of the improved draft device in use,

Fig. 2 is a plan view of the same applied,

Fig. 3 is a fragmentary horizontal sec-

55 tion through the device,

Fig. 4 is a central vertical longitudinal section through the same,

Fig. 5 is a side elevation of the device, the view illustrating the various positions of the same with relation to the plow,

Fig. 6 is a perspective of a portion of the draft device,

Fig. 7 is a group perspective of the releasing means for the plow beam.

In the drawings wherein for the purpose 65 of illustration is shown a preferred embodiment of the invention, the numeral 10 designates the beam of a plow provided as usual with a downwardly extending share 11. In this instance the source of power is in the 70 nature of a tractor 12 though it is obvious that draft animals may be employed for operating the plow in lieu of the motor operated tractor.

The improved draft device herein illustrated and forming the subject of this application comprises a body member 15 which includes a head 16 and a pair of spaced parallel rearwardly extending side members 17.

As illustrated in Figs. 6 and 7, the rear portion of the head 16 is reduced to form an attaching shank 18 adapted to be arranged between the front ends of the side members 17 and having openings 19 aligned 85 with openings 20 in the said side members for the reception of connecting bolts 21.

When the spaced parallel side members 17 have been connected to the head 16 through the medium of the bolts 21, these 90 elements form a unit which is U-shaped in plan view. The reduced thickness of the shank 18 with relation to the head forms pairs of shoulders 23 on opposite sides of the shank 18 and adjacent the upper and 95 lower sides of the same, which shoulders flatly engage the front ends of the side members 17 for strengthening the connection between the parts.

The opposed sides of the spaced parallel 100 side members 17 are adapted to be arranged on opposite sides of the forward portion of the plow beam and are provided with downwardly inclined slots 25 communicating with longitudinally extending slots 26. As particularly illustrated in Fig. 6, the longitudinally extending slots 26 formed in the opposed faces of the side members 17 extend rearwardly from and have communication 105 with downwardly extending slots 27. In 110

other words, it might be said that the slots 26 and 27 in each side member 17 form a single L-shaped slot having communication with the rearwardly inclined slot 25 extending out through the upper side of the member 17. A driving connection is provided between the forward portion of the beam 10 and said draft head or body 15 through the medium of laterally projecting lugs or pins 28 which, when in their final position, are seated in the lower ends of the vertical slots 27. When a forward pull is exerted on the body 15 the rear vertical walls of the slots 27 are engaged with the adjacent sides of the pins 28 whereby a forward pull is applied to the beam 10. When it is desired to remove the beam 10 from connection with the draft body 15, the pins 28 are moved upwardly and rearwardly through the slots 26, and then upwardly and out through the rearwardly inclined slots 25.

The head 16 of the body 15 is provided with a longitudinally extending elongated slot 30 through which a connecting bolt 31 is extended. As illustrated in Fig. 3, the bolt is extended through apertures in a pair of ears 33 forming a part of a clevis 34 connected to the draw bar cap 36 of the tractor through the medium of a connecting pin 37. The apertured ears 33 of the clevis 34 are arranged in spaced parallel relation on opposite sides of the head 16 and inwardly of the apertured heads 39 of a pair of draft rods 40.

The draft rods 40 which have connection with the clevis through the medium of the bolts 31, are slidably extended through pairs of laterally projecting ears 42 formed on opposite sides of the side members 17.

A yieldable driving connection is provided between the rods 40 and the laterally projecting ears 42 of the side members 17 by a pair of retractile coil springs 43 which surround the rods and are confined between one ear of each pair and tensioning nuts 44 having threaded engagement with the free end portions of the rods. When a forward pull is exerted on the clevis 34, the draft rods 40 are of course moved forwardly and when the load is not unusually great the retractile coil springs 43 will contract but a small extent and will transmit the pull to the side members 17 through the forward ears 42. The forward pull thus exerted on the side members 17 is transmitted through the pins 28 to the beam 10 of the plow so that the plow is caused to move forwardly with the tractor. When the share of the plow is being moved through ground not unusually hard, the springs 43 will yield only slightly and, should the plow share engage a tree stump or other obstruction, the draft rods 44 will be moved forwardly with relation to the laterally projecting ears 42 whereby a yieldable driving connection is provided be-

tween the plow share and the tractor. The yieldable driving connection thus provided absorbs the shock transmitted through the beam to a considerable extent so that the tractor is not subjected to injurious strains. 70

The yieldable connection between the plow share and the tractor as above described serves only as a means for absorbing minor shocks incident to travel and is not adapted to entirely break the driving connection between the plow beam and the draft body 15. The means employed for entirely breaking the driving connection between the beam of the plow and the body 15 in the event of the plow share engaging an obstruction sufficient to break the share if the pull is continued, comprises a pair of spaced parallel dogs 50 of elongated formation. The dogs 50 act as a tripping or elevating device for removing the laterally projecting pins 28 from the vertical slots 27 when the strain on the draft head 15 exceeds the resisting capacity of the retractile coil springs 43. The forward portions of the spaced parallel dogs 50 are slidably arranged in longitudinally extending grooves 51 formed in opposite sides of the head 16 and aligned with longitudinal grooves 52 in opposite sides of the side members 17. As illustrated in Fig. 3, the spaced parallel dogs 50 are provided in their forward portions with elongated slots 53 aligned with the elongated slot 30 formed in the head 16 and receiving the transversely extending connecting bolt 31. It will be noted that the dogs and consequently the slots 53 terminate short of the forward end of the slot 30 so that the forward end walls of the slots 53 will be engaged by the bolt 31 prior to the engagement of the bolt with the forward end of the slot 30. That is to say, when the clevis 33 moves the bolt 31 forwardly, the dogs 50 will be engaged and moved forwardly before the bolt 31 reaches the limit of its forward movement. Under ordinary conditions the draft rods 40 positioned the bolt 31 approximately in the intermediate portions of the slots 53 so that the dogs are not moved forwardly until the springs 43 have yielded considerably and the forward movement of the rods 40 is continued. 110

As illustrated in Fig. 7, the rear portions of the dogs 50 are formed with longitudinally extending slots 55, the upper sides 56 of which normally overhang the pins 28 for locking the same in the vertical slots 27. The pair of spaced parallel dogs 50 are connected for simultaneous movement by a transversely extending connecting pin 57 joined with the dogs intermediate their ends. 120

As particularly illustrated in Figs. 3 and 4, the head 16 is formed with a longitudinally extending socket 58 which receives a retractile coil spring 59 engaging the transversely extending connecting pin 57 for urg- 130

ing the spaced parallel dogs rearwardly with relation to the head. By this means the longitudinally extending slots 55 of the dogs are urged rearwardly so that the upper sides 56 of the slots 55 are caused to overhang the pins 28 for securing the latter within the slots 27. The reduced shank 18 of the head 16 is provided with slots 60 on opposite sides of the retractile coil spring 59 so that the pin 10 may partake of a limited movement longitudinally of the head.

When the load is increased to an extent sufficient to contract the springs 43, the pin or bolt 31 is of course moved relatively forwardly in the slot 30 of the head 16 and is caused to engage the forward end walls of the slots 53 so that the dogs are caused to move forwardly. This occurs only when the load is sufficient to contract the coil springs 20 43 to an extent greater than will allow the coil springs to absorb the shock. In other words, when the load becomes excessive, the bolt 31 is moved forwardly for imparting a corresponding movement to the dogs. This 25 forward movement of the dogs causes the overhanging portions 56 of the same to be removed from above the slots 27 so that no means remain for confining the pins 28 within the slots. As the forward movement of 30 the dogs continues elevating devices or ejectors in the form of shoulders 61 having their forward ends inclined, as indicated at 62, are engaged with the adjacent sides of the pins 28 for removing the same from within the 35 slots 27. When the pins 28 are removed from within the slots 27 the same enter the longitudinal slots 26 and are passed out through the upwardly inclined slots 25 thereby releasing the driving connection between 40 the plow beam and the body 15.

The inclination of the plow share 11 may be varied by adjusting the position of the beam 10 with relation to the body 15. The adjusting means for the beam 10 comprises 45 a pair of laterally projecting lugs 65 extended out through opposite sides of the beam and selectively received in pairs of vertically spaced recesses 66 in the rear ends of the side members 17. By setting the laterally projecting lugs 65 in the lowermost pair 50 of recesses 66, the beam and consequently the plow share is inclined only slightly, and by positioning the laterally projecting lugs 65 in the uppermost pair of recesses 66, the 55 cutting depth of the plow share 11 is increased. This adjustment may be effected without in any way interfering with the shock absorbing means or with the operation of the means for breaking the driving connection 60 between the body 15 and the plow beam when the strain becomes excessive.

It will readily be observed that the draft body and the dogs may move pivotally about the bolt 31. Consequently, the side members 65 and the dogs may be inclined relative

to the plow beam and the upper edges of the side members disposed under the lugs 28 which may thus be easily caused to register with and enter the slots 25 in the side members. Then, of course, the shifting of 70 the draft body longitudinally rearward with respect to the beam will bring the lugs or pins 28 through the slots 26 to the slots 27 in which they will be locked by properly adjusting the dogs, the beam being thereby 75 securely coupled to the draft body. The body 15 may be connected to the source of power, which in this case is the tractor 12, through the medium of the clevis 34. As 80 the tractor propels the plow, the retractile coil springs yield to an extent sufficient to absorb slight increases in the load as the result of the plow share striking a rock or other obstacle. Of course, when the clevis exerts a forward pull on the bolt 31, the 85 bolt partakes of a limited movement within the slots 30 and 53 but under ordinary circumstances the increase in the load will not be sufficient to cause the bolt 28 to move the dogs 50 forwardly. However, should the plow share engage a large stump or other obstruction which would be likely to injure the plow share or the tractor, the coil springs 43 will yield so as to allow the draft rods 40 to partake of a longitudinal movement through the apertured ears 42. This longitudinal movement of the draft rods 40 is accompanied by a forward movement of the bolt 31 within the slots 30 and 53. 90 When the bolt on its forward movement engages the end walls of the slots 53, the dogs are caused to move forwardly so that the overhanging portions 56 of the same are removed from above the pins 28. The continued forward movement of the dogs 50 causes the ejectors 62 of the same to be engaged with the pins 28 whereupon the pins will pass out through the rearwardly extending slots 26 and thence out through the upwardly and rearwardly inclined slots 25. 95 In this manner the source of power is automatically disconnected from the plow beam when the strain or load becomes greater than is safe for the plow share or the 100 tractor. 110

It is to be understood that the form of the invention herewith shown and described is to be taken as a preferred embodiment of the same and that such minor changes in construction and arrangement of parts may be made as will remain within the spirit of the invention and the scope of what is claimed. 120

Having thus described the invention, what 125 is claimed as new is:

1. In a draft device, the combination of a body member having a head provided with a longitudinal slot closed at its ends, a bolt extending through said slot, means mounted 130

- on said bolt for connecting the same to a source of power, draft rods mounted on said body member and engaged by said bolt, springs providing a driving connection between said draft rods and said body member, means for coupling the body member to a device to be towed, and a releasing device slidably mounted upon said bolt and adapted to disconnect said coupling means.
- 10 2. In a draft device, the combination of a relatively fixed body member, means whereby the same may be connected to a source of power, a beam, a stationary seat in fixed position on said body member, draft-applying means on the beam engaging in the seat on the body member, cushioning means for absorbing minor increases in the load, and means carried by the body member to release said draft-applying means from the 20 seat on the body member when the load exceeds a predetermined limit.
- 15 3. In a draft device, the combination of a body member, means whereby the same may be connected to a source of power, a beam having lugs extending into said body member for providing a driving connection between the beam and the body member, an ejecting device for removing said lugs from within said body member when the load 30 increases beyond a predetermined limit, and cushioning means interposed between said body and the means for connecting the same with a source of power.
- 35 4. In a draft device, the combination of a body member provided with slots, means whereby the same may be connected with a source of power, a beam having pins received within the slots in the body member, and means active when the draft exceeds a 40 predetermined limit to eject said pins from within the slots whereby to permit separation of the body member and the beam under continued draft.
- 45 5. In a draft device, the combination with a body having side members provided with slots, of a beam arranged between said members of said body and provided with pins received within said slots, dogs slidably carried by the side members and having means 50 for normally retaining said pins within said slots, and means to remove said dogs from locking engagement with said pins when the draft exceeds a predetermined limit.
- 55 6. In a draft device, the combination with a body having side members provided with slots in their opposed sides, of a beam having pins slidably arranged in said slots and normally seating in the front ends of the same, dogs arranged on the opposite sides of said 60 beam and having their rear portions normally overhanging said pins for securing the same within said slots, said dogs being provided with means for ejecting said pins from their seats at the front ends of said slots, a bolt having connection with said dogs, and

yieldable draft devices connected with said bolt.

7. In a draft device, the combination with a body having a slot and a seat at the front end of the slot, of a beam provided with a pin received within said slot and engaging said seat, a dog having a longitudinal slot receiving said pin for normally confining the pin within the seat at the end of said first named slot, and means for moving said dog longitudinally away from said pin, the rear portion of said dog being provided with means for ejecting said pin from the seat in the first named slot when the draft exceeds a predetermined limit.

8. In a draft device, the combination with a body having side members provided with L-shaped slots, of a beam provided with laterally projecting pins received within said L-shaped slots, dogs having means for securing said pins within said slots, a bolt connected to the forward portion of said dogs for moving the same longitudinally away from said pins, the rear portions of said dogs being provided with upwardly inclined ejectors for removing said pins from within the vertical portions of said slots, and yieldable draft devices connected to said body and dogs.

9. In a draft device, the combination with a body having spaced parallel side members formed with L-shaped slots and upwardly inclined slots, of a beam provided with laterally projecting pins seated in the inner portions of said L-shaped slots, a pair of dogs having means for securing said pins within said L-shaped slots, a draft device connected to the forward portion of said dogs, the rear portions of said dogs being provided with means for ejecting said pins from the inner portions of said L-shaped slots when the draft exceeds a predetermined limit, said pins being free to pass out through said upwardly inclined slots upon leaving said inner portions of the L-shaped slots, and means whereby said body may be connected to a source of power.

10. In a draft device, the combination with a body inclusive of a head and side members, of a beam having means for engaging said side members and receiving draft therefrom, a bolt extending through said head, yieldable draft rods connected with said bolt, a clevis attached to said bolt for connecting the same to a source of power, and ejecting devices having connection with said bolt for releasing the beam from the side members when the draft exceeds a predetermined limit.

11. In a draft device, the combination with a body inclusive of a head and side members provided with slots, of a beam having laterally projecting pins received within said slots, a bolt extending through said head, yieldable rods connected to said body

and said bolt, dogs slidably carried by said body and provided with slots receiving said bolt, the rear portion of said dogs being provided with means for releasing said pins 5 from locking engagement with said slots in the side members when the draft exceeds a predetermined limit.

12. In a draft device, the combination with a body member inclusive of a head and 10 side members provided with L-shaped slots and upwardly inclined slots, of a beam arranged between said side members and having laterally projecting pins received within said L-shaped slots, said head being provided with a longitudinally extending slot, a bolt extending through the slot in said head, yieldable draft rods connected to said bolt and said body, a clevis attached to said bolt, ejecting means for releasing the pins 15 from locking engagement with the L-shaped slots, said ejecting means being slidably carried by said body and having connection with said bolt, and means whereby the ejecting means may be positioned to normally 20 confine said pins within said L-shaped slots.

13. In a draft device, the combination with a body inclusive of a head provided with a longitudinal slot and side members 25

connected to said head, of a beam detachably connected to said side members, a bolt slidably extended through the longitudinal slot in said head, draft rods arranged on opposite sides of said side members and connected to said bolt, springs for providing yieldable connection between said draft rods and said 30 side members, a releasing device having sliding connection with said bolt and adapted for disconnecting said beam from said members when the draft exceeds a predetermined limit, and an attaching device for connecting said bolt to a source of power. 35

14. In a draft device, the combination with a body member, and means whereby the same may be connected with a source of power, of a beam having laterally projecting pins detachably connected to said body member, and releasing devices carried by said body member and adapted to release the laterally projecting pins of said beam from locking engagement with said body 40 member when the load exceeds a predetermined limit. 45

In testimony whereof we affix our signatures.

EDWIN G. HINES. [L. S.]
CHARLES S. MYERS.
